TYPE-WRITING MACHINE.

1,151,839.

Specification of Letters Patent. Patented Aug. 31, 1915.

Application filed January 7, 1914. Serial No. 810,712.

To all whom it may concern:

Be it known that I, FRANK C. URSPRUNK, a citizen of the United States, residing in New York city, in the county of New York and State of New York, have invented certain new and useful Improvements in Type-Writing Machines, of which the following is a specification.

This invention relates to typewriting machines, and particularly to means for enabling the use of a plurality of sets of type-bars in which the types or characters of one set are of a different width or size from those of the other set and require letter-spaces on the work-sheet of greater width for the characters of one set than for those of the other set.

This invention relates principally to machines of the kind disclosed in an application of Stephen T. Smith, Serial Number 802,337, filed November 22, 1913, in which a paper carriage may be translatable from one set of types to another set, each set having its own keys. The type sets may be placed side by side, and the carriage may run upon a multiple-length track which enables it to coöperate with either set of types at the will of the operator. Thus the number of types for use with a single paper carriage may be doubled; and in order to permit the use of larger types with one set, or characters requiring wider space on the work-sheet than required by the characters of the other set, the invention provides means whereby the paper carriage, when co-operating with one set of types, is fed through letter-space distances of greater extent than when coöperating with the other set. Thus larger types may be used with one set than with the other, or the wider type blocks may be devoted to italics or script, or the two keyboards could be devoted to different languages in which the characters of one language preferably occupy a wider space than those of the other language, or any other desired combination of sets of characters could be employed. For example, the small letters of one set may be used for portions of a piece of work, and other portions may be emphasized by the use of the larger types of the other set or the latter may be used for titles, head lines,

etc., or various other combinations may be used.

This invention also gives the operator 55 the choice of writing letters, bills or other documents with either small sized or large sized type, as may be best suited for the particular work in hand, one machine serving for both purposes, whereas with ordinary 60 typewriters, two separate machines would be required. Also different styles of type might obviously be employed on the different sets of type-bars.

The present invention is also of value in 65 adapting one machine for writing a number of different languages where the characters of one language require a wider space than the characters of another language. Thus, for example, the larger types might be used 70 for writing a language such as the Korean language in which a number of characters are grouped together and printed by a single type-stroke, such a group requiring a wider space than the individual characters of another language, such as English, which could 75 comprise the smaller types.

In the preferred manner of carrying out the invention, there may be employed two Underwood front strike machines, which 80 may be placed side by side and fixed together, the usual carriage tracks being replaced by multiple-length front and rear rails, and a single carriage may be run on said rails and movable from one part of the 85 double machine to the other.

The invention is not limited to the use of two keyboards, as more than two keyboards and two sets of types might obviously be employed. 90

The carriage track may be of sufficient length to permit the carriage to be shifted along the rails into coöoperative relation with the desired set of types, each set of types being provided with its own keyboard. The 95 letter-space feed of the carriage, when co-operating with any set of type keys, is controlled by an escapement rack on the carriage running in mesh with an escapement pinion mounted upon the machine frame. 100 In accordance with the present invention, and to permit the feed to be varied for the different sets of type, a plurality of feed racks are provided upon the carriage, a

separate rack and letter feed mechanism being employed for each set of types, said mechanisms being so proportioned that the letter spacings correspond with the size of type employed in the corresponding set.

Other objects and advantages will herein-after appear.

In the accompanying drawings, Figure 1 is a perspective plan view of one form of machine made in accordance with the present invention. Figs. 2 and 3 are detail views of the escapement mechanism at the left-hand and right-hand sides of the machine, respectively. Fig. 4 is a rear perspective view of the mechanism shown in Fig. 2, the escapement wheel being omitted. Fig. 5 is a sectional elevation taken about centrally of the right-hand main portion of the machine, as shown in Fig. 1. Figs. 6 and 7 are views of types of different sizes for use at the left-hand and right-hand sides of the machine, respectively.

In practising the invention in the form illustrated, the frameworks 1 and 2 of two Underwood front-strike typewriting machines may be rigidly secured by fasteners 3 (Fig. 5) upon a common base 4, and they may also be rigidly joined by a rear carriage rail 5 and a front carriage rail 6, each of which rails extends from the left-hand end of the frame 1 to the right-hand end of the frame 2. Upon these rails may travel a carriage 7, which, as shown, is an Underwood typewriter carriage of the usual construction. This carriage has front rolls 8 which run in the groove of the rail or track 6, and collars 9 which engage the rear guide rail 5.

The carriage is preferably provided with a plurality of feed racks, one for each set of type-bars 12 and 13; these racks 10 and 11 being adapted to be brought into mesh with pinions 14 and 15 mounted upon the right-hand and left-hand frames 2 and 1, respectively. The feed racks 10 and 11 may be connected together and form part of a swinging frame 16 pivoted on the carriage 7 and operable by a key 17 to lift the racks and thus release either rack from its pinion. The pinion 14 may be connected in the usual manner through a one-way driving pawl 18 to an escapement wheel 20 controlled by a dog rocker 21, the latter actuated by type keys 22 mounted on levers 23 connected through sub-levers 24 to type-bars 12, which have heels 25 to thrust backwardly a universal bar 26 mounted on links 27 and adapted to strike the dog rocker 21. The type keys 28 connected to the type-bars 13 operate in like manner through a universal bar and a dog rocker 21^a to control an escapement wheel 29.

Assuming the carriage 7 is in the right-hand writing field, as shown in Fig. 1, the operator manipulates the keys 22 to swing

the type-bars 12 upwardly and rearwardly to bring the types 30 thereon against the front face of the platen 31, and the carriage is fed along step-by-step in the usual manner, the rack 10 being in mesh with the pinion 14 and permitting the carriage to move forwardly at each type stroke a distance determined by the pitch of the teeth on escapement wheel 20, and the diameter of the pinion 14, such distance being preferably the distance between adjacent teeth of the rack 10. Ribbons 32 mounted on spools 33 operate in the usual manner.

An index pointer 34 on the carriage moves over a scale 35 on the front rail 6; the graduations on the scale being spaced to correspond with the letter-space movements of the carriage as controlled by the escapement wheel 20.

If at any time, the operator wishes to use the set of types 36 in the left-hand system, he depresses the release key 17 to lift the rack 10 free from the pinion 14, and then shifts the carriage to the left to bring the work-sheet to the writing position for the types 36. The key 17 is then released and permits the rack 11 to drop into mesh with the pinion 15 (Fig. 2). Writing may then proceed in the usual manner, the keys 28 being manipulated to actuate the types 36.

By comparing Figs. 2 and 3, it will be observed that the rack 10 can only mesh with the pinion 14, and also that the rack 11 can only be brought into mesh with the pinion 15. The rack 10 being somewhat lower than the rack 11, holds the latter away from the pinion 14, and the pinion 15 being located forward of the rack 10 and out of alignment therewith, the rack 11 is permitted to move downward to engage the pinion 15.

As indicated on the drawings, the diameter of the pinion 15 meshing with the rack 11, is greater than that of the pinion 14 on which runs the rack 10, thus providing for feed of the carriage through comparatively wide letter-space distances when in the zone of the types 36. The same result might be obtained in other ways, as for example, by having the teeth on the two escapement wheels 20 and 29 of different pitch. These letter-spaces may, for example, be in the ratio of "8" to "10," as indicated by the scales 35 and 37, the graduations of which are spaced to correspond with the letter feed movements of the carriage when controlled through the racks 10 and 11, respectively. Obviously the ratio, as well as the absolute value of the letter-space distances might be varied, or the positions of escapement mechanisms interchanged.

The carriage is connected by a strap 38 to a spring-barrel 39 by which the carriage may be propelled for its letter feed movements throughout its range of travel on the rails 5 and 6.

- At Fig. 6 is shown a type-bar 13 provided with upper and lower case types either of which may be called into use by a shift key 40, and the type-bars 12, as indicated in Fig. 7, are also provided with upper and lower case types either of which may be called into use by the operation of a shift key 41. Thus on a single piece of work all of the different types may be employed.
- 10 The shift keys 40 and 41 are for temporary use, each being held depressed while the type keys are manipulated. The keyboards are also provided with permanent or locking shift keys 42 and 43, which lock the platen 31 in the upper shift position. The shift keys are connected to the shift rail 44 through suitable mechanism comprising a shift frame 45, whereby when a shift key is depressed, the rail 44 is lifted and through 15 a shift roll 46 on the platen frame lifts the platen frame and platen to the upper shift position.

At the right-hand end of the frame 2 is the usual adjustable margin gage 47 for 20 limiting the return stroke of the carriage in determining the beginning of a new line. The usual left-hand margin gage is omitted from the frame 2 in order to permit the shifting of the carriage across to the frame 30 1, and the usual right-hand margin gage is omitted from the frame 1 for the same reason. Fig. 1, however, carries the usual adjustable left-hand margin gage 48. Each keyboard is also provided with a space key, 35 said keys shown at 49 and 50, and in general each section of the machine coöperating with the carriage forms a complete typewriter of itself.

Variations may be resorted to within the 40 scope of the invention, and portions of the improvements may be used without others.

Having thus described my invention, I claim:

1. A typewriting machine comprising a 45 traveling carriage, and a plurality of key-operated letter-feed mechanisms for effecting letter-feed movements of the carriage, the individual movements effected by one of said mechanisms being of different extent than those effected by the other of said mechanisms, said carriage movable in letter-feed direction from position to coöperate with one of said mechanisms into position to coöperate with the other of said mechanisms.

2. A typewriting machine comprising, in combination, a plurality of type-systems, keys for operating the same, a paper-carriage adjustable to coöperate with either 60 type-system, and means actuated by said keys for effecting letter-feed movements of the carriage through letter-space distances of greater width when the carriage is coöperating with one type-system than when 65 it is coöperating with the other type-system.

3. A typewriting machine comprising in combination a plurality of type-systems, each system having its individual printing center, keys for operating said type-systems, a paper-carriage adjustable to either 70 printing center, and letter-feed mechanisms individual to the two type-systems and operable by said keys to effect letter-space movements of the carriage, the individual letter-spacings for one system being greater 75 than those for the other.

4. A typewriting machine comprising in combination a plurality of keyboards, a plurality of type-systems, one for each keyboard, operated by the keys thereof, a paper-carriage, a track along which the carriage is movable into position to coöperate with either type-system, means actuated by the keys of one keyboard, for effecting letter-space movements of a given extent when the 85 carriage is coöperating with one type-system, and means actuated by the keys of the other keyboard for effecting letter-space movements of a different extent when the carriage is coöperating with the other type- 90 system.

5. A typewriting machine comprising the combination of a plurality of keyboards, a plurality of type-systems, one for each keyboard, operated by the keys thereof, a paper-carriage, a multiple length track along which the paper-carriage is movable to enable it to coöperate with either type-system, a propelling spring for the carriage, an escapement mechanism actuated by the keys 95 of one keyboard to permit letter-feed movements of the carriage of a given extent, and a second escapement mechanism actuated by the keys of the other keyboard to effect letter-space movements of a different extent.

6. In a typewriting machine, the combination with a plurality of type-systems, each having its own individual printing center, and a set of operating keys individual 110 to each type-system, of a paper-carriage, means to effect a relative shifting movement between the paper-carriage and the type-systems to enable the carriage to coöperate with either type-system, and a separate letter-feed mechanism associated with each type-system and actuated by the corresponding set of keys for effecting letter-space movements of the carriage, the extent of such movements being greater for one system 115 than for the other.

7. In a typewriting machine, the combination of a plurality of type-systems, a traveling paper-carriage shiftable from position to coöperate with one of said systems to position to coöperate with the other of said systems, letter-feed racks on the carriage, an escapement mechanism for one of said racks when the carriage is in position to coöperate with one type-system, and a second escape- 125 130

- ment mechanism for the other rack when the carriage is in position to coöperate with the other type-system, one of said escapement mechanisms operable to effect letter-feed movements of the carriage through wider intervals than those effected by the other escapement mechanism. 5
8. In a typewriting machine, the combination of a plurality of type-systems, a traveling paper-carriage shiftable from position to coöperate with one of said systems to position to coöperate with the other of said systems, letter-feed racks on the carriage, an escapement mechanism for one of said racks when the carriage is in position to coöperate with one type-system, a second escapement mechanism for the other rack when the carriage is in position to coöperate with the other type-system, one of said escapement mechanisms operable to effect letter-feed movements of the carriage through wider intervals than those effected by the other escapement mechanism, and a key for lifting said racks to release either rack from its escapement mechanism and permit the carriage to be shifted from one type-system to the other. 15
9. In a typewriting machine, the combination of a plurality of type-systems; a set of operating keys individual to each type-system; a carriage shiftable into position to coöperate with any one of said type-systems; a plurality of letter-feed racks on said carriage, one for each type-system; pinions co-operating with said racks and selectively engaged thereby; and a separate key-actuated mechanism associated with each pinion for controlling the rotation thereof, said pinions being of different diameters, thereby to effect letter-feeding movements of different extents. 20
10. In a multiplex typewriting machine, the combination of a plurality of keyboards, arranged side by side; a set of types individual to the keys of each keyboard for operation thereby; a carriage shiftable into position to coöperate with any one of said sets of types; and a separate mechanism operatively connected with the keys of each keyboard for controlling the letter-feeding movements of the carriage, the extent of such movements being greater for one of said mechanisms than for another. 25
11. In a multiplex typewriting machine, the combination of a multiple-length track; a carriage traveling thereon; a key-actuated mechanism for effecting a step-by-step letter-feeding movement of said carriage during the travel of the carriage over one predetermined length of track; and a separate key-actuated mechanism for effecting a step-by-step letter-feeding movement of said carriage, of different extent from the first-named movement, during the travel of said carriage over another predetermined length of track. 30
12. In a typewriting machine, the combination of a carriage having different definite stages of travel during a single run; and a separate key-actuated mechanism for effecting a step-by-step letter-feeding movement of said carriage during each of said stages, said movements differing in extent for each stage. 35
13. In a typewriting machine, the combination of a carriage; a key-actuated mechanism for effecting a step-by-step letter-feeding movement of said carriage during a predetermined portion of its run; and a separate key-actuated mechanism for effecting a step-by-step letter-feeding movement of said carriage of different extent from the first-named movement during the remainder of such run. 40
14. In a typewriting machine, the combination of a carriage having different definite stages of travel during a single run; a separate key-actuated mechanism for effecting a step-by-step letter-feeding movement of said carriage during each of said stages, said movements differing in extent for each stage and means to effect the selective operation of said mechanisms. 45
15. In a typewriting machine, the combination of a carriage; a key-actuated mechanism for effecting a step-by-step letter-feeding movement of said carriage during a predetermined portion of its run; a separate key-actuated mechanism for effecting a step-by-step letter-feeding movement of said carriage of different extent from the first-named movement during the remainder of such run, and means to effect the selective operation of said mechanisms. 50
